UNITED STATES PATENT OFFICE.

CHARLES H. BURK, OF ORIZABA, MEXICO, ASSIGNOR OF ONE-HALF TO H. C. PIERCE, OF ST. LOUIS, MISSOURI, TRUSTEE FOR THE PIERCE-FORDYCE OIL ASSOCIATION, OF TEXAS.

OIL-BURNING APPARATUS.

1,171,413.

Specification of Letters Patent. Patented Feb. 15, 1916.

Application filed February 10, 1914. Serial No. 817,743.

To all whom it may concern:

Be it known that I, CHARLES H. BURK, a citizen of the United States, residing at Orizaba, State of Vera Cruz, Mexico, have 5 invented certain new and useful Improvements in Oil-Burning Apparatus, of which the following is a specification.

This invention as specified relates to new and useful improvements in oil burning apparatus.

The object of the invention is to provide an apparatus comprising a burner located at the front end of a fire box fed by steam and oil pipes the latter of which passes 15 through a super-heater and leads from a storage tank in which the oil is heated and placed under pressure.

Other objects of the invention are the provision of means for cleaning the oil pipes 20 and the burner; and the provision of a safety device whereby the supply of oil from the oil tank is automatically cut off in case of fire.

A still further object of the invention is to 25 provide an apparatus of the character described that will be strong, durable, efficient and simple and comparatively inexpensive to produce, also one in which the several parts will not be likely to get out of working 30 order.

With the above and other objects in view, the invention has relation to certain novel 35 features of construction and operation, an example of which is described in the following specification and illustrated in the accompanying drawings, wherein:

Figure 1 is a diagrammatical view of the oil burning apparatus. Fig. 2 is a horizontal cross-sectional view on the line W—W 40 of Fig. 1. Fig. 3 is a horizontal cross-sectional view on the line X—X of Fig. 1. Fig. 4 is a detail of the super-heater. Fig. 5 is a detail of the burner and adjusting means. Fig. 6 is a front elevation of the 45 burner. Fig. 7 is a plan view of the burner. Fig. 8 is a section on the line Y—Y of Fig. 7 and Fig. 9 is a cross section on the line Z—Z of Fig. 7.

In the drawings the numeral 1 designates 50 the fire box of a boiler furnace, 2 the front end and 3 the rear end. As shown in Fig. 2 an opening 4 is provided in the rear end of the fire box. In this opening a burner 5 is horizontally disposed. As shown in Fig. 5 a yoke 6 is fixed on a bracket 7 secured to

the outer side of one end of the fire box which we will call the rear end. Trunnions 8 are journaled in the upper ends of the yoke 6. A pair of adjacent ears 9 project horizontally from the outer end of the burner 60 and pivotally receive the upper end of an eye rod 10 as shown in Figs. 5 to 9 inclusive. The lower end of the rod 10 passes through a plate bracket 11 secured to the under side of the fire box. The eye rod is screw 65 threaded and receives nuts 12 bearing on opposite sides of the bracket 11. By adjusting these nuts the burner through the agency of the rod is swung on its trunnions and its angle of inclination with relation to a horizontal plane varied.

The trunnions 8 have central passages 14 and 15 respectively extending transversely of the burner and communicating with the chamber 19 within the burner. The chamber 75 is divided into two compartments by a transverse web 16 of irregular contour and an extension 20 of this web separates passages 17 and 18 extending longitudinally of the burner as shown in Figs. 8 and 9. The passage 15 admits oil into the chamber 19 which is deflected by the web 16 into the passage 17; while steam admitted through the passage 14 to the chamber 19 is deflected by the web 16 into the passage 18.

The oil is discharged from the inner end of the burner by way of the passage 17. The steam passage 18 is below the oil passage 17 and has its discharge end contracted and partially closed by a nozzle plate 21 removably set into the end of the burner. The plate 21 may be renewed when worn or burned out. The opening for the discharge of steam is restricted whereby the steam is ejected in a fine spray and mixed with the oil at the point of combustion. By observing Fig. 1 it will be noted that the burner is located at the rear end of the fire box and that at the front end of the fire box a brick wall 2' is provided which acts as a target 90 and against which the steam and oil are ejected. Sufficient space for admitting air is left around the burner in the opening 4 but additional air openings 22 may be provided in the wall 3' if desired. Where the burner is applied to a locomotive boiler the end 3 would be toward the front of the locomotive and the end 2 at the cab.

A very important feature of the invention is the means and apparatus for sup.¹¹⁰

plying steam and superheated oil to the burner. This apparatus comprises a storage tank 25 in which a heating coil 27 is supported above the bottom. Exhaust steam from a superheater 41 is conveyed by a pipe 42 to a branch pipe 28^a which leads through the bottom of the tank to the coil. Steam from the coil is conveyed by a short pipe 42^a to the pipe 42 at a point above the pipe 28^a. It is not always necessary to use the heating coil but when it is used a valve 60 located in the pipe 42 between the pipes 28^a and 42^a is closed whereby the exhaust steam from the superheater is circulated through the coil. When it is desired to cut out the heater the valve 60 is opened and a valve 61 located in the pipe 28^a is closed thus permitting the exhaust steam to escape through the pipe 42 to atmosphere. The heating coil maintains the oil in a flowing condition. A steam pipe 26 leads from the boiler to a pipe 28 which terminates in a pipe 29 leading to the passage 14 of the burner and in which a controlling valve 30 is included.

An oil pipe 31 leads from a valve 32 in the bottom of the oil tank. The valve 32 has a spring pressed rod extending through the top of the tank and is normally closed by the spring. A collar 34 is fixed in the upper end of the valve rod and is engaged by one end of a centrally pivoted lever 35 which has its opposite end connected to a cord 36. The cord 36 is placed under tension whereby the valve 32 is lifted and held under tension of the spring pressed rod. The cord 36 is coated with tar or other fast burning material so that in case of fire the cord will ignite and release the rod 33 whereby the valve will be closed.

An air pump has connection with the tank 25 by means of a pipe 38 and a pipe 39 mounted in the top of the tank. A safety valve 40 is mounted at the upper end of the pipe 39 and is of suitable construction and arranged to relieve the air pressure in the tank when said pressure becomes excessive. The oil in the tank 25 is heated and placed under pressure to flow into the pipe 31. A steam tight drum 41 surrounds the pipe 31 and forms a superheater for the oil passing through said pipe. Exhaust steam from the superheater is conveyed by the pipe 42. Live steam may be introduced from the pipe 28 by means of a pipe 43 in which a cutoff valve 44 is included. Exhaust steam from the pump 37 is conveyed to the drum 41 by means of a pipe 45.

It is apparent that the steam for superheating may be supplied to the drum in various ways. A pipe 46 leads from the

pipe 31 to the passage 15 of the burner and has included therein a controlling valve 47. Suitable connection is made between the pipes 29 and 46 and the burner whereby the latter may be swung. Superheated oil is highly combustible and is of great advantage in an oil burner.

For the purpose of cleaning the pipe 31 the pipe 46 and the passages 15 and 17 of the burner, a pipe 48 leading from the live steam pipe 28 is connected to the pipe 31. A valve 49 is mounted on the pipe 48 for cutting off the passage of steam to the pipe 31. Between the pipe 48 and the tank 25 a valve 50 is mounted in the pipe 31. When it is desired to clean the parts 31, 46, 15, and 17 the valve 50 is closed and the valve 49 is opened thereby live steam will flow through the pipes 31 and 46 and the passages 15 and 17 thus removing any deposits or obstructions and cleansing the oil outlet of the burner.

What I claim is:

1. In an oil burning apparatus, a burner, an oil storage tank, an oil pipe leading from the tank to the burner, a superheater surrounding the oil pipe, a source of steam supply, a steam pipe leading therefrom to the burner and to the superheater, an exhaust pipe leading from the superheater, a coil connected with said exhaust pipe and located in the oil storage tank, combined with valved connections arranged so as to cut in and cut out the coil with the exhaust pipe, substantially as described.

2. In an oil burning apparatus, the combination with the boiler and fire box of a boiler furnace, of a burner located in the fire box, an oil storage tank, an oil pipe leading from the tank to the burner, a superheater surrounding the oil pipe, a heating coil located in the tank, an exhaust pipe leading from the superheater, a steam pipe leading from the boiler to the burner, a connection between the steam pipe and superheater, a cut-off valve included in the last named connection, a branch pipe leading from the exhaust pipe to the coil, a cut-off valve included in said branch pipe, a discharge pipe leading from the coil to the exhaust pipe, and a valve in the exhaust pipe between the connections with the branch and discharge pipes.

In testimony whereof I have signed my name to this specification in the presence of two subscribing witnesses.

CHARLES H. BURK.
